Fig. 1

Fig. 2

Fig. 3

FIG. 1 is a perspective view of a clock showing my new design;

FIG. 2 is a front elevational view; and

FIG. 3 is a left side elevational view, the right side elevational view being a mirror image thereof.

The rear of the clock housing is plain. The essential features of the design reside in the portions shown in full lines.

I claim:

The ornamental design for a clock, substantially as shown and described.
